SPRING HOLDING MEANS FOR ELECTRIC SHAVER SHEARING HEAD

Harold S. Kachline, Lancaster, and Armand R. Van Baelen, Quarryville, Pa., assignors to Schick Incorporated, Lancaster, Pa., a corporation of Delaware

Filed Jan. 5, 1960, Ser. No. 574
5 Claims. (Cl. 30—43)

The invention relates generally to the mounting of the shearing head on the case or motor housing of an electric shaver.

More particularly, the invention is concerned with the provision of a mounting and holding means for a shearing head unit of the type adapted to be located in a channel formed in one end of the case and having a headed locking member protruding from its under side, the construction including a spring clip associated with the case and adapted to receive and snap engage the headed locking member.

The invention will be readily understood from the following description and the accompanying drawings illustrating the preferred form.

FIG. 1 of the drawings is a partly broken out elevation of a shaver incorporating the invention;

FIG. 2 is an enlarged view of the upper or head end of the shaver of FIG. 1, partially sectioned;

FIG. 3 is a still further enlarged and broken out section on the line 3—3 of FIG. 2;

FIG. 4 is a broken out plan view of the head receiving channel portion of the shaver;

FIG. 5 is a section on the line of 5—5 of FIG. 4; and

FIG. 6 is an exploded view of the major head mounting components.

The illustrated shaver will be seen to include a case or motor housing 1 incorporating a head channel, generally designated 2 (FIGS. 3 and 4) at its upper end, the channel being formed and bounded by the upstanding side walls 3 and the bottom wall 4.

The particular type of shearing head unit illustrated forms no part of the present invention but consists of a pair of identical shearing heads 5 disposed side by side, with an intervening spacer bar 6 and held together by clips 7. Formed integrally with and depending from the lower edge of the spacer bar is a headed enlargement or locking member 8 which, as described below, is utilized for securing the head unit in position in the case channel. The illustrated shaver is of the known split case type, the case consisting of like halves or shells mating on the line 9. The case halves are marked 10 and 11, respectively.

The headed enlargement or locking member 8 depends within an opening 15 in the bottom wall of the head unit channel and also located in opening 15 is an upwardly, U-shaped opening spring clip, generally designated 17. This clip is secured against bodily movement in relation to the case and its arms 16 are shaped and biased to receive and snap engage the member 8 when the latter is pushed into the wall opening 15 and the head unit seated in its channel in the case. No other manipulation is required to position and secure the head unit and, of course, it is as readily removed by simply pulling it upwards out of the channel to free the member 8 from the clip 17. It will be apparent that where, as in this instance, the case consists of two centrally mating halves, the opening 15 is conveniently formed part in one case half and part in the other. It may be noted that the arch 18 cut in the clip arms 16 is simply to provide clearance for mechanism having nothing to do with the present invention.

In this preferred form, the means for securing the clip 17 against bodily movement in relation to the case includes two pairs of laterally projecting portions, namely,

2

the upper flanges 23 and the lower tabs 24. The upper flanges are received in and located by recesses 25 formed in the upper surface of the channel bottom wall, that is, one in each case half; and the lower tabs 24 are received in and located by recesses 26 formed in the walls of the opening 15, below the upper surface of bottom wall 4. Like the opening 15, recesses 26 may be formed part in one case half and part in the other.

Seated on the upper surface of the channel bottom wall 10 is a plate 30 which is secured to the case and which has an opening 31 so dimensioned that the portions 32 of the plate, bordering the longer sides of the opening, overlie and thereby confine the clip flanges 23. It will be understood that, while the clip 17 is thus secured against bodily upward movement when the head unit is being withdrawn from its channel, the recesses 25 are deep enough to avoid having the plate 30 rigidly clamp the clip flanges 23, sufficient clearance being provided to permit the arms of the clip to spread and return to accommodate the passage of the head 8.

The means for securing the plate 30 to the shaver case includes screws 33 which, it will be noted, are disposed beneath and normally concealed by the head unit. These screws, in this instance, serve also as part of the means for 25 securing the case halves together at the head or upper end of the shaver. The screws pass freely through plate 30 and the bottom wall of the head unit channel and, at their lower ends, are threaded into nut members in the form of clamps 34. These clamps have diverging upturned ends 35 which engage the nether or under surface of the channel bottom wall. Specifically, they engage and embrace the portions 36, 37 of the respective case halves so that, as the screws are tightened, the clamps draw the case halves together and, of course, hold them against 35 separation.

The shaver is shown as having clippings receptacles 40 located one at each end of the shearing head unit and hinge mounted by means of springs 41; and, while this feature is not part of the present invention, it may be noted that the inner ends of these springs may be seated 40 on the channel bottom wall and clamp to it by plate 30.

It will be recognized that the details of the invention are subject to modification to suit the conditions in hand and that the described adaptation of the invention to the 45 particular shaver illustrated is intended only to exemplify the preferred form. In the light of the foregoing, the following is claimed:

1. In an electric shaver of the kind including a shearing head unit having a headed locking member protruding from its under side, a case of which one end incorporates a channel to receive the shearing head unit and an opening in the bottom wall of the channel to receive the headed locking member, the improvement which comprises an upwardly opening spring clip disposed in said opening 50 to receive and snap-engage the locking member, the upper surface of the bottom wall of the channel having recesses therein adjacent said opening and the walls of the opening, below the said upper surface, also having recesses 55 therein, said clip having upper and lower laterally projecting portions, the former adapted to seat in the first mentioned recesses and the latter adapted to seat in the second mentioned recesses, a plate seated on the said upper surface of the bottom wall of the channel and overlying the upper, laterally projecting portions of the clip and means securing the plate to the case.

2. In an electric shaver of the kind including a shearing head unit having a headed locking member protruding from its under side, a case of which one end incorporates a channel to receive the shearing head unit and an opening in the bottom wall of the channel to receive the headed locking member, the improvement which com-

prises an upwardly opening, U-shaped spring clip disposed in said opening and adapted for snap-engagement with and from the headed locking member when the shearing head is, respectively, pushed into and pulled out of the said channel, the clip having lower, laterally projecting portions and the side walls of the said opening having recesses spaced from the upper surface of the bottom wall of the channel and adapted to receive said laterally projecting portions, whereby the clip is held against removal from the case.

3. In an electric shaver of the kind including a shearing head unit having a headed locking member protruding from its under side, a case of which one end incorporates a channel to receive the shearing head unit and an opening in the bottom wall of the channel to receive the headed locking member, the improvement which comprises an upwardly opening, U-shaped spring clip disposed in said opening and adapted for snap-engagement with and from the headed locking member when the shearing head is, respectively, pushed into and pulled out of the said channel, the upper surface of the bottom wall of the channel having recesses therein adjacent the said opening, the said clip having upper, laterally projecting portions adapted to seat in said recesses, a plate seated on the said upper surface of the bottom wall of the channel and overlying the said laterally projecting portions of the clip and means securing the plate to the case, whereby the clip is held against removal from the case.

4. In an electric shaver of the kind including a shearing head unit having a headed locking member protruding from its under side, mating case halves incorporating a channel to receive the shearing head unit and an opening in the bottom wall of the channel to receive the headed locking member, the improvement which comprises an upwardly opening, U-shaped spring clip disposed in said opening and adapted for snap-engagement with and from

the headed locking member when the shearing head is, respectively, pushed into and pulled out of the said channel, a plate seated on said bottom wall and overlying portions of the clip, clamp members disposed within and embracing portions of both of the case halves and screws passing through said plate and bottom wall and threaded into the said clamp members.

5. In an electric shaver of the kind including a shearing head unit having a headed locking member protruding from its under side, mating case halves incorporating a channel to receive the shearing head unit and an opening in the bottom wall of the channel to receive the headed locking member, the improvement which comprises an upwardly opening U-shaped spring clip disposed in said opening to receive and snap engage the locking member, the clip having laterally projecting tabs and the opposite walls of the said opening, below the bottom wall of the channel, having recesses which are open at one end at the mating face of one of the case halves to receive the clip tabs, the other case half overlying and closing the open ends of the recesses and thereby securing the clip against removal from the assembled case halves and means securing the case halves against separation.
